UNITED STATES PATENT OFFICE.

CHARLES KOSHALKO, OF JOHNSTOWN, PENNSYLVANIA.

AUTOMATIC GAS-VALVE.

SPECIFICATION forming part of Letters Patent No. 691,784, dated January 28, 1902.

Application filed June 17, 1901. Serial No. 64,896. (No model.)

To all whom it may concern:

Be it known that I, CHARLES KOSHALKO, a citizen of the United States, residing at Johnstown, in the county of Cambria and 5 State of Pennsylvania, have invented certain new and useful Improvements in Automatic Gas-Valves; and I do hereby declare the following to be a full, clear, and exact description of the invention, such as will enable others skilled in the art to which it appertains 10 to make and use the same.

My invention has relation to automatic gas-valves, and has for its object the provision of means whereby the gas will be positively and 15 automatically shut off from the burner if for any reason it should be accidentally extinguished, as by being blown out or by failure of the supply from the main or in any other manner; and my invention consists in 20 the novel construction, combination, and arrangement of parts hereinafter described and claimed.

Referring to the accompanying drawings, Figure 1 is a side elevation; Fig. 2, a vertical 25 sectional view; Fig. 3, a top view looking down on the burner from above; and Fig. 4, a detail of the key by means of which the gas is turned on and off in the ordinary manner, all these views being shown on an enlarged 30 scale, so that the parts may be plainly seen and their construction understood.

A designates a gas-burner screwed onto the end of a gas-pipe B. Within the burner A is a horizontal partition C, which is formed with 35 a valve-seat on which seats a valve D, the stem of which is connected with a rock-shaft E, the said rock-shaft being journaled in the walls of the burner. The valve D is normally closed by a spring F, coiled around the 40 valve-stem between the valve and a bridge F', which extends across the burner-tube and by which the stem is guided. The rock-shaft E projects through the wall of the burner and has fixed on its outer end the lever G. A 45 bent tube H is attached to the burner at one side, and said tube, which is of substantially U shape, has a bulb g on one of its legs, while the other leg is open at its upper end and contains a piston H', which is attached to one end 50 of the lever G.

I designates a rod that hangs from the other end of the lever G and has at its lower

end a hook i, which engages in a spiral slot k in a turn-key K, which may be either the ordinary cock of the gas-fixture or simply a 55 turn-key fixed to the burner for the purpose of operating the hook i. Above and to one side of the spiral slot k a lug L is formed on the key, the purpose of which is to catch the hook when it has been swung to one side by 60 traveling in the slot.

The tube H is intended to contain mercury or other material which is readily expanded by heat, and the tube is so placed with relation to the flame of the burner that when the 65 gas is burning the heat of the flame will keep the mercury or other material in the tube in an expanded condition and the piston H' elevated, in which position the valve D will be held off its seat and the gas allowed to flow 70 freely through the burner.

Operation: When it is desired to light the gas, the key K is turned in the direction of the arrow, and the hook i, engaging with the spiral slot, will be directed to one side and 75 will when it reaches the end of the slot engage with the lug L, and the further turning of the key will draw the rod I down and open the valve D. The gas may now be lighted, and the heat from the flame will act on the 80 expansive material in the tube H and bring such material up against the lower end of the piston H' and hold such piston up, and thus keep the valve D open so long as the gas is ignited. If by accident the flame is extin- 85 guished, material in tube H will contract and allow the piston H' to descend and the valve D to close, thus at once and effectually closing off the flow of gas. The hook i drops to one side of the lug L when the pressure of 90 the hand is released from the key K, and hence this hook offers no resistance to the movement of the rock-shaft when it is being turned by the descent of piston H'.

Having described my invention, I claim— 95

1. In an automatic gas-valve, the combination of a burner, a valve within the same and normally closed by a spring, a piston connect- 100 ed to said valve and adapted to open the same against the pressure of said spring, a tube in which said piston works, an expansive mate- rial in said tube and means whereby said valve is opened and held open until the ex- pansion of the material in the tube will oper-

ate the piston and maintain said valve open so long as the gas is ignited, substantially as described.

2. In an automatic gas-valve, the combination with the burner, a valve therein, and a spring bearing on said valve to normally close the same, of a rock-shaft journaled in the burner and connected with the valve, a lever on said rock-shaft, a tube containing an expansive material, a piston in said tube attached to said lever and actuated by the expansive material, a rod depending from said lever and having a hook at its lower end, a turn-key having a spiral groove in its side 15 and a lug at the end of said groove to engage the said hook.

3. In an automatic gas-valve, the combina-

tion with a valve arranged within the burner and means for manually opening said valve, of means for causing the valve to close comprising a piston, connections between the piston and the said valve, a vessel in which said piston works, arranged within the heating sphere of the flame, an expansive and contractive material in said vessel controlling the movement of the piston, and a spring to cause the piston to follow the contractions of said material substantially as described.

In testimony whereof I have affixed my signature in presence of two witnesses.

CHAS. KOSHALKO.
